#661

Patented July 15th 1854

Des. 661

William Douglas and Benjamin Douglas of Middletown 65
Letters Patent No. 661. Dated July 11 1854.

The schedule referred to in these Letters Patent, and making part of the same
To all whom it may concern.

Be it known that we, William
Douglas and Benjamin Douglas, both of the City of Middletown
in the County of Middlesex, and State of Connecticut,

Have invented a new and useful design for Wall curbs,
and we do hereby declare that the following is a full, clear
and exact description of the construction and character of the
same; reference being had to the accompanying drawings
which make a part of this specification, in which

Figure 1. is a perspective view of the wall curb, shew-
ing the side on which the crank is placed.

Figure 2. is a plan, or direct view, of the opposite side
of the same showing the figure or design
complete, and unobscured.

We make the Wall curb, in two parts A. and B. with the

upper part A. in the form of a semicircle or semi-ellipse and the lower part nearly vertical, but slightly enlarging downward, so as to give symmetry to the whole power, or design, as represented in the drawings.

The upper part, A, we ornament (in the castings) with semicircular mouldings, (as represented at a,) and radiating corrugations, or ribs, as represented at b. in both figures. And the lower part B, we ornament (also in the castings,) with vertical corrugations, or flutings, as represented at c, c, and with a point formed substantially, as represented at b. in both figures. and we secure the parts A and B, together by clamps, as shown at h. and h. On one side, (as shown in Figure 1,) we place a crank, a, which is cast, or made in one piece with the ratchet wheel, e. in which the ratchet, or pawl, works all substantially as represented in Figure 1.

What we claim as our Invention, and desire to secure by Letters Patent, is the design displayed by a combination of the form, and ornaments as represented,
